UNITED STATES PATENT OFFICE.

HANS PETER HANSON, OF CHICAGO, ILLINOIS.

CLOSURE FOR AUTOMOBILE RADIATORS AND THE LIKE.

Application filed May 23, 1921. Serial No. 471,784.

To all whom it may concern:

Be it known that I, HANS P. HANSON, a citizen of the United States, residing at Chicago, in the county of Cook and State of Illinois, have invented certain new and useful Improvements in Closures for Automobile Radiators and the like, of which the following is a specification.

The present invention has to do with improvements in closures for automobile radiators and the like. While the invention is particularly useful in connection with closures for automobile radiators, still it will be understood that various features of the invention may be used to great advantage in connection with other classes of service.

It has become very customary to place a thermal indicator on the radiator cap for showing the internal condition of the engine. These attachments are comparatively expensive. Furthermore, when such attachment is mounted upon the radiator cap, it is a very simple matter to remove it by simply unscrewing the cap from the radiator. It has, therefore, been very easy for persons to steal the indicators by simply unscrewing the radiator caps.

One of the objects of the present invention is to provide means for locking the radiator closure in position, so that it cannot be removed except by the use of a proper key. In this connection another object is to combine the temperature indicator with the closure in such a manner that the temperature indicator cannot be removed from the closure except from the inside, thus making it impossible to remove the thermal indicator without first unlocking the closure.

Another object of the invention is to so associate the thermal indicator with the closure that the closure when unlocked may be readily removed by simply turning the thermal indicator which for this purpose acts more or less as a handle. More particularly an object in this connection is to provide a closure composed of two parts one of which may be permanently attached to or associated with the radiator shell and is largely ornamental, the other portion of the closure being removable when unlocked and carrying the thermal indicator.

Another object of the invention is to so place the locking device with respect to the various parts and particularly with respect to the closure that when the closure is locked in position, the locking device will be her-

metically sealed from the interior of the radiator so as to effectively prevent the steam which may be generated from reaching the lock. This will prevent the lock being corroded or otherwise damaged by said steam.

Other objects and uses of the invention will appear from a detailed description of the same which consists in the features of construction and combinations of parts hereinafter described and claimed.

In the drawings:

Figure 1 shows a vertical cross section through the upper portion of a radiator shell having applied thereto a closure and locking device embodying the features of the present invention;

Fig. 2 shows a horizontal cross section taken on the line 2—2 of Fig. 1, looking in the direction of the arrows;

Fig. 3 shows an end view of one of the bars of the device shown in Figs. 1 and 2, being the bar within which is located the lock;

Fig. 4 shows a vertical fragmentary section through a modified form of closure in which said means are provided for locking the thermal indicator to the cap;

Fig. 5 shows a horizontal section taken on the line 4—4 of Fig. 5 looking in the direction of the arrows;

Fig. 6 shows a perspective view of one of the locking wedges of the arrangement shown in Figs. 4 and 5;

Fig. 7 shows a perspective view of a modified form of ring and locking wedges;

Fig. 8 shows a fragmentary vertical section taken through another modified form of locking device for locking the cap to the radiator shell; and

Fig. 9 shows a perspective view of the locking ring used in the arrangement in Fig. 8.

Referring first to the construction shown in Figs. 1 and 2, the radiator shell is designated by the numeral 10. It has the upstanding neck 11 of the usual form. The neck illustrated in Fig. 1 is internally threaded and is intended to receive an internal closure. A cap 12 is associated with the neck 11. Said cap has a downwardly depending exteriorly threaded neck 13 which threads onto the radiator neck 11, and to which it may be locked from the inside as by means of a set screw 14. The cap 12 may be of any convenient form or appearance

or design, but the one illustrated in Figs. 1, 2, and 3, is provided with a circular body portion 15 having a pair of oppositely placed horizontal arms 16 and 17. For purposes of convenience these arms are shown as having the end enlargements 18 and 19, but it will be understood that the form and appearance of the arms is largely a matter of design, and may be changed within wide limits. In fact the arms themselves might be entirely eliminated and the body portion of the cap may also be varied within wide limits of form and appearance.

The cap is provided with a central vertically extending passage 20 through which access may be had to the interior of the radiator as for filling it with water. The upper end of the passage 20 is enlarged and presents an upwardly facing annular seat 21. The enlarged portion of the passage is threaded as shown at 22. A closure plug 23 threads into the enlarged end of the passage and closes its upper end. This closure plug may carry a thermal indicator 24 or any suitable ornamental or symbolizing device, or any other element by means of which the plug may be conveniently rotated for threading and unthreading. In fact, in some cases, the plug itself may be allowed to extend above the top of the cap, such upwardly extending portion presenting a convenient means whereby the plug may be rotated.

When a thermal indicator is used, its neck 25 may be extended down through the plug, so that its lower end is presented to the thermal condition of the interior of the radiator. A nut 26 threaded onto the lower end of the neck 25 serves to lock the thermal indicator to the plug 23 from the inside, so that the thermal indicator cannot be removed from the plug without injury until the plug itself has been removed from the cap. Ordinarily a steam-tight gasket 27 will be provided between the nut 26 and the lower face of the plug.

I have provided suitable means for locking the plug to the cap, so that these two parts can only be separated by the use of a proper key. In the arrangement shown said locking device takes the form of a pin 28 working in the arm 16, which pin may be thrown in or out by the rotation of a key introduced into the key opening 29 in the enlarged end 18 of the arm 16. When the key is introduced into the opening 29, it may then be rotated so as to retract the pin 28 into the position shown in Figs. 1 and 2. When the key is to be withdrawn it must first be turned back into the normal position, and this act of turning will in itself project the pin 28 inwardly. The back and forth movement of the pin 28 when it is turned by the use of a key inserted into the key opening 29 may be accomplished in the following man-

ner: The locking pin 28 is provided with a diagonally extending slot 29^a in its surface; and the arm 16 is provided with an inwardly projecting pin 29^b which reaches into the slot 29^a. When the locking pin 28 is turned, it is moved back and forth by reason of the engagement of its slot 29^a with the fixed pin 29^b of the arm 16. A suitable socket 30 is provided in the plug 23 into which the pin 28 will enter when so projected. This socket 30 may be of the exact size necessary to receive the pin or it may be of enlarged size, as shown in Fig. 2, in which case it will not be necessary to bring the plug 23 into exact position with respect to the cap before the parts may be locked together. Nevertheless, when using the enlarged socket, such as shown in Fig. 2, the plug cannot be unscrewed from the cap without first retracting the pin 28.

In order to prevent steam which may be generated within the radiator from gaining access to the pin 28 and locking mechanism, I have illustrated a sealing gasket 31 between the lower face of the plug 23 and the shoulder 21. Ordinarily a steel ring 32 will also be placed in this location in addition to the gasket itself. When a steel ring is used, it should be set on top of the gasket, as shown in Fig. 1, so that the gasket itself will not be subjected to a direct rubbing action when the plug is threaded up tight.

It will be observed that with the arrangement above described, the thermal indicator or other useful or ornamental device itself serves as the means for rotating the plug; that said device is locked to the plug from the inside, so that it can only be removed from the plug without injury after the plug has been removed from the cap; and that the plug may be locked to the cap, so that it cannot be removed without injury except by the use of a proper key.

The arrangement shown in Figs. 1 and 2 makes no special provision for locking the thermal indicator to the plug in a non-rotatable manner beyond the locking action secured by the use of the nut 26. This will in most cases be sufficient. However, in Figs. 4 and 5, I have shown a modified arrangement in which the plug itself is provided with a downwardly tapered opening 33 through which the neck 25 of the thermal indicator passes, said opening 33 receiving one or more locking wedge blocks 34. Each of these locking wedge blocks may be of the form shown in Fig. 6. Its inner face is provided with a cutting edge 35 adapted to dig into the material of the neck 25 when the lock 34 is wedged into position. The block or blocks 34 are set into a collar 36 against which the nut 26 operates, so that when said nut is tightened up, it forces the wedge blocks 34 firmly into place.

In Fig. 7 I have shown a modified form 130

of wedge block locking device to take the place of that illustrated in Figs. 4 and 5. In this case one or more wedge blocks 37 are mounted in a flexible ring 38, so that 5 these parts become a unit. When this device is used, the nut 26 will bear directly against the lower face of the ring 38. This ring itself will have sufficient flexibility to enable the wedge blocks 37 to take the 10 desired position in the locking position.

The arrangement shown in Figs. 1 and 2 includes a cap for use with an internally threaded radiator neck. In Figs. 8 and 9 I have shown a modified construction in 15 which the cap is intended to co-operate with an externally threaded radiator neck 39. In this case the cap has the internally threaded downwardly extending collar 40 which threads into the neck 39. A seal 41 extends 20 inwardly from the collar 40 and presents an upwardly facing shoulder 42. A locking ring 43 sets into said shoulder, said locking ring having a downwardly depending lug 44 which reaches to a point low enough 25 down to receive a set-screw 45. Said set-screw is threaded through the lug 44 and engages the inner face of the neck 39. It is thus impossible to remove the cap 12 without first loosening up the set-screw 45 from 30 the inside.

It will be observed that when the cap has been locked to the neck of the radiator shell, it becomes in effect a portion of said neck, being rigid therewith. Therefore, in some 35 cases the use of a cap as a separate and distinct element may be dispensed with and the cap may be locked directly to the neck of the radiator shell.

While I have herein shown and described 40 only certain embodiments of my present invention, still I do not limit myself to the said embodiments except as I may do so in the claims.

I claim:

45 1. In a device of the class described, the combination with the neck of a radiator shell, of a cap threaded onto said neck, said cap having a vertically extending through passage, the upper portion of said passage being threaded, there being an upwardly 50 facing shoulder at the lower end of said threaded portion, a plug threaded into said portion, a steam-tight gasket between the shoulder and the lower face of the plug, a thermal indicator extending through the 55 plug, means for securing the thermal indicator to the plug by the use of a locking device on the inner end of the thermal indicator, means for securing the cap to the neck of the radiator shell by the use of an interior locking device accessible 60 only through the plug opening when the plug is removed, and a radially extending and radially movable locking pin in the cap, there being a peripheral socket in the threaded portion of the

70 plug adapted to receive the inner end of said locking pin when projected inwardly, and means in the cap for shifting the position of said pin only by the use of a suitable key, substantially as described.

2. In a device of the class described, the combination with the neck of a radiator shell, of a cap threaded onto said neck, said cap having a vertically extending through 75 passage, the upper portion of said passage being threaded, there being an upwardly facing shoulder at the lower end of said threaded portion, a plug threaded into said portion, a steam-tight gasket between the shoulder and the lower face of the plug, a thermal indicator extending through the 80 plug, means for securing the thermal indicator to the plug by the use of a locking device on the inner end of the thermal indicator, means for securing the cap to the neck of the radiator shell by the use of an interior locking device accessible only when the plug is removed, and means for locking the plug against unthreading from the cap except by the use of a special key, substantially as described.

3. In a device of the class described, the combination with the neck of a radiator shell, of a cap threaded into said neck, said cap having a vertically extending through 95 passage, the upper portion of such passage being threaded, a plug threaded into said portion, a thermal indicator extending through the plug, means for securing the thermal indicator to the plug by the use of a locking device on the inner end of the thermal indicator, means for securing the cap to the neck of the radiator shell by the use of an interior locking device accessible 100 only through the plug opening when the plug is removed, and means for locking the plug against unthreading from the cap except by the use of a special key, substantially as described.

4. In a device of the class described, the combination with the neck of a radiator shell, of a cap mounted on said neck, said cap having a vertically extending through 115 passage, the upper portion of said passage being threaded, a plug threaded into said portion, a thermal indicator extending through the plug, means for securing the thermal indicator to the plug by the use of a locking device in the inner end of the thermal indicator, means for securing the cap to the neck of the radiator shell by the use of an interior locking device accessible only through the plug opening when the plug is removed, and means for locking the plug against unthreading from the cap except by the use of a special key, substantially as described.

5. In a device of the class described, the combination with the neck of a radiator shell, of a cap mounted on the said neck,

said cap having a vertically extending through passage, a separate plug mounted within the cap, a thermal indicator extending through the plug, means for securing the thermal indicator to the plug by the use of a locking device on the inner end of the thermal indicator, means for securing the cap to the neck of the radiator shell by the

use of an interior locking device accessible only through the plug opening when the plug is removed, and means for securing the plug against movement with respect to the cap except by the use of a special key, substantially as described. 10

HANS PETER HANSON.
